UNITED STATES PATENT OFFICE

157,107

COMBINED PORTABLE TRAY AND HEATER

George W. Walker, Pleasant Ridge, Mich., assignor to Radiant Heater Corporation, New York, N. Y., a corporation of New York

Application November 1, 1948, Serial No. 149,426

Term of patent 14 years

(Cl. D81—10)

To all whom it may concern:

Be it known that I, George W. Walker, a citizen of the United States, whose post office address is 46 Oakdale, Pleasant Ridge, Michigan, have invented a new, original, and ornamental Design for a Combined Portable Tray and Heater, of which the following is a specification, reference being had to the accompanying drawing forming a part thereof, wherein:

Figure 1 is a perspective view of the side, end and top of a combined tray and heater, showing my new design;

I claim:

The ornamental design for a combined portable tray and heater, as shown.

GEORGE W. WALKER.
